UNITED STATES PATENT OFFICE.

ELLEN M. JOHNSON STUBBS, OF PHILADELPHIA, PENNSYLVANIA.

PORABLE WASHTUB.

1,107,862.

Specification of Letters Patent. Patented Aug. 18, 1914.

Application filed August 22, 1913. Serial No. 786,068.

To all whom it may concern:

Be it known that I, ELLEN M. JOHNSON STUBBS, a citizen of the United States, residing in the city and county of Philadelphia, State of Pennsylvania, have invented a new and useful Portable Washtub, of which the following is a specification.

My invention consists of a portable wash tub more particularly for laundry purposes, 10 the same being adapted to be placed within a sink or upon a table, bench, etc., and composed of a body with means for discharging the wash water therein, either into a sink or by the attachment of a hose or conveyer 15 into another receptacle, or adapting such water to be directed to a drain, sewer, gutter, etc., the construction of parts being hereinafter described and the novelty thereof of pointed out in the claim.

20 The invention is satisfactorily illustrated in the accompanying drawing, but the important instrumentalities thereof may be varied, and so it is to be understood that the invention is not limited to the specific arrangement and organization shown and described.

25

Figure 1 represents a longitudinal vertical section of a laundry tub embodying my invention. Fig. 2 represents a top or plan 30 view thereof. Fig. 3 represents a vertical section on an enlarged scale of the water discharging device thereof. Fig. 4 represents a similar section, one of the members being in different position from that shown 35 in Fig. 3.

Similar numerals of reference indicate corresponding parts in the figures.

Referring to the drawings, 1 designates the body of the tub, the same being provided 40 with handles 2, and feet 3, for evident purposes.

4 designates a nipple which is secured to the bottom of the tub and has perforations 5 in the side thereof forming communication 45 with the interior of the tub for the discharge of the wash water from the tub and straining the same in its entrance into said nipple.

6 designates a vertically disposed tubular 50 stopper whose lower portion has a closed side and has an open bottom which is adapted to fit slidingly over the nipple 4 so as to close the top and perforated side of the latter and prevents thereby the discharge 55 of water from the body of the tub into the said nipple, said tube having its

upper portion constitute the handle 7 whereby the tube may be raised so as to uncover the perforations 5 of the nipple and thus permit the discharge of water from the body 60 into the nipple. The nipple is extended downwardly below the bottom of the tub, and consequently below the side perforations 5 forming the neck 8 which is screw-threaded for the attachment therewith of 65 the screwthreaded portion of the coupling of a hose or pipe 9, whereby the latter may be placed in communication with said nipple and consequently with the interior of the body of the tub.

70 The operation is as follows: When the tub is placed in a sink, it is supplied with water of the required temperature, the stopper 6 being lowered to full extent so as to cover the top of the nipple and side perforations thereof. As the top of the nipple is open and so in communication with the interior of the stopper, the latter having an open bottom, as has been stated, should the tub be supplied with an excess of water, 80 it will overflow at the top of said stopper into the same, and so enter the nipple, whereby it will discharge into the sink or the hose or pipe 9. When the washing is accomplished, the stopper is raised whereby 85 the perforations of the nipple are uncovered and thus the wash water may enter the nipple through said perforations and so discharge the water from the tub, said perforations acting as strainers, preventing im- 90 proper matter from entering the nipple and clogging the same. The water flows through the nipple and so enters the sink from which it may escape through the usual outlet thereof, it being noticed in Fig. 1, that the 95 bottom of the neck is above the floor of the sink so that it will not be clogged by said floor. When the tub is placed on a bench, table, chair, the hose or pipe 9 is screwed to the nipple whereby when the washing is ac- 100 complished and the stopper raised or opened, the wash water may escape through the nipple into said hose or pipe, when it may be directed by the latter to a bucket or pail, a sewer, drain, gutter, or other place. 105 After the tub has been used, it may be removed from the sink, bench, etc., and located out of the way, as desired. The body of the tub may be made of suitable sheet metal which is light, strong and durable 110 and easily kept clean, and the nipple and stopper of cast metal, but to the material, I

do not limit myself. In order to connect the nipple firmly with the bottom of the tub, I form the lower end thereof with the flange 10, which is brazed, soldered, or otherwise firmly connected with said bottom. The screw-threaded portion 11, of the nipple 4, is a downward extension of the body of the latter, constituting a neck or nozzle, and this with said body and the flange 10 may be cast in one piece, thus forming a strong structure of the nipple and adapting the latter to sustain the stopper thereon in its upright position, said stopper when in closed position, has its lower end abutting upon the flange 10. The lower end of the nozzle 11 terminates above the bottom of the feet 3 and so is adapted to discharge the wash water from the body into the sink, but when the tub is rested on a wash bench, table or the like such nozzle is sufficiently above the latter to screw the plug of the hose 9 thereto and allow a portion of said hose to pass between the feet 3 and be directed to a bucket or pail or other receptacle as hereinbefore stated. The washing, bluing and rinsing of the articles in the tub may be accomplished in any desired manner, and the outlet nipple may be opened as often as required to dis-

charge the wash water and closed to admit of the tub being replenished with fresh water. When it is desired to apply a wringer to the tub, there is attached to an end or side of the same the loop, hoop or keeper 12, which latter is adapted to receive the clamp or other suitable member of the frame of the wringer so as to support said wringer properly on the tub.

Having thus described my invention what I claim as new and desire to secure by Letters Patent, is:—

A portable wash tub comprising a body with supporting feet, a hollow nipple in the bottom of said body having a perforation in its side, and a securing flange seated on said bottom, a nozzle depending from said nipple for detachable connection with a discharge conveying tube, and a vertically disposed overflow stopper having its lower portion movably fitted on said nipple and its bottom end adapted to close against said flange.

ELLEN M. JOHNSON STUBBS.
